(57) **CLAIM**

The ornamental design for a joint of a figurine, as shown and described.

DESCRIPTION

FIG. 1 is a front perspective view of a joint of a figurine; FIG. 2 is a front elevation view thereof, the rear elevation view being a mirror image thereof; FIG. 3 is a left side elevation view thereof, the right side elevation view being a mirror image thereof; FIG. 4 is a top plan view thereof; FIG. 5 is a bottom plan view thereof; FIG. 6 is a front perspective view thereof, shown in use as a knee joint; FIG. 7 is a front perspective view thereof, shown in use as a shoulder joint; and, FIG. 8 is a front perspective view thereof, shown in use as an elbow joint. The broken lines shown in FIGS. 6, 7 and 8 illustrate portions of a figurine that form no part of the claimed design. The dot-dash broken lines define the bounds of the claimed design and form no part thereof.

1 Claim, 4 Drawing Sheets
